UNITED STATES PATENT OFFICE.

EDGAR C. BROWN AND WILLIE B. MAY, OF WADESBORO, NORTH CAROLINA.

CAR-DOOR LOCK.

1,144,345.

Specification of Letters Patent. Patented June 29, 1915.

Application filed November 28, 1914. Serial No. 874,451.

To all whom it may concern:

Be it known that we, EDGAR C. BROWN and WILLIE B. MAY, citizens of the United States, residing at Wadesboro, in the county 5 of Anson and State of North Carolina, have invented new and useful Improvements in Car-Door Locks, of which the following is a specification.

The invention relates to door locking 10 mechanism, and more particularly to the class of sliding door locks for use on grain or box cars.

The primary object of the invention is the provision of a door lock wherein the door 15 of a grain or box car is secure when closed and can only be unlocked for the opening thereof from beneath the body of the car and through the use of a hand crank or key, thus obviating a surreptitious entry to the 20 car through the doorway, the locking mechanism being of novel form and construction to assure the perfect working thereof.

Another object of the invention is the provision of a door lock of this character where- 25 in it will automatically fasten the door on the closing thereof, thereby obviating repeated use of the hand crank or key when it is desired to fasten the door.

A further object of the invention is the provision of a door lock of this character wherein its mechanism is mounted solely 30 within the body of the car and is operated from beneath the same to allow the opening of the door for an entrance to the car.

A still further object of the invention is the provision of a car door lock of this character which is simple in construction, readily and easily installed within the body of the car, thoroughly reliable and efficient in its 35 operation, automatically operable for the locking of the door closed, and also which is inexpensive in manufacture.

With these and other objects in view, the invention consists in the construction, combination and arrangement of parts as will be hereinafter fully described, illustrated in the accompanying drawing, and pointed out in the claims hereunto appended.

In the drawing:—Figure 1 is a frag- 50 mentary side elevation of a box car with its door, the locking mechanism constructed in accordance with the invention being within and the door fastened closed. Fig. 2 is a vertical transverse sectional view through 55 the car. Fig. 3 is a sectional view on the

line 3—3 of Fig. 1, showing the lock mechanism in top plan. Fig. 4 is a vertical longitudinal sectional view through the car.

Similar reference characters indicate corresponding parts throughout the several 60 views in the drawings.

Referring to the drawings in detail, A designates generally a portion of the body of the car, which is of the grain or box type, and B the sliding door at the side thereof 65 for closing the doorway therein, as usual, the door being supported through the medium of hangers 10 and tracks 11 of any ordinary well-known construction for permitting movement thereof to opened or closed 70 position. Mounted interiorly of the body A of the car is the door locking mechanism hereinafter fully described.

The door locking mechanism comprises a sliding latch bolt 12 having the latch end 75 thereof rounded, while its remaining portion is of squared formation in cross section, and is disposed transversely of the body A of the car to move horizontally, the rounded end of the said bolt being slidable 80 through a guide plate 13 which is fixed on the inner face of the outer side wall of the body A, and this rounded end of the said bolt is of a length to project through the side of the body A so as to normally intersect 85 the path of movement of the door B for the locking of the same closed.

Located at one side and slightly below the bolt 12 and fixed interiorly of the body A on the outer side wall thereof is a bracket 90 14 forming a bearing for a vertically disposed operating shaft 15 which also passes through a bearing plate 16 fixed to the flooring of the body of the car, the shaft being projected through the flooring into a recess 95 17 therein so as not to protrude beneath the bottom of the car, the end of the shaft 15 within the said recess 17 being squared as at 18 for the detachable connection thereof with a crank or key 19 which is used for the 100 turning of the shaft to operate the lock mechanism hereinafter more fully described.

Fixed to the bottom of the body A of the car exteriorly thereof and surrounding the recess 17 therein is an escutcheon plate 20 105 through which is introduced the crank or key 19 for its engagement with the shaft when the lock mechanism is to be operated for the unlocking of the door.

On the shaft 15 above the bracket 14 is a 110

disk 21 formed with the respective arms 22 and 27, the said arm 22 being formed with a bifurcation 23 in which is engaged a lug 24 fixed in and depending from the sliding 5 latch bolt 12 so that on the turning of the disk 21 the latch bolt 12 will be thrown in one direction for retracting it to permit the opening of the door when the shaft is rotated. Swingly connected to the bracket 10 14 is a trip cam plate 25 carrying a trip cam 26, with the cam surface of which is adapted to engage the arm 27, which serves as a trip arm formed on the said disk 21, the plate 25 being connected with the bracket 14 through 15 the medium of a hinge 28 to permit vertical swinging movement under the action of the swing arm 27 when the lock mechanism is operated.

Pivotedly supported above the latch bolt 20 12 is a locking detent 29, the pivot 30 therefore being disposed near one end, while mounted on the shorter end of the said detent 29 is a link 31 which is also connected to the swinging plate 25, and on the longer 25 end of the detent 29 is carried a weight 32 which serves to gravitate the said detent into locking engagement in a notch 33 formed in the bolt 12 so as to prevent the sliding thereof to released position after it 30 has been thrown for locking the door B closed.

Connected with the bearing plate 13 is one end of a coiled retractile spring 34 which has its opposite end connected with the bolt 35 12 so that when it has been thrown to unlatching position by operating the shaft 15 and the door opened the said spring will serve to automatically throw the bolt 12 to locked position when the door is closed.

40 In the operation of the locking mechanism, it will be assumed that the door B has been closed and the locking mechanism is in a position for fastening the door. Now, to open the door it is necessary to engage the key 19 with the squared end 18 of the shaft 15, and this is accomplished by going beneath the body A of the car, whereupon on the turning of the crank the shaft 15 is rotated, and simultaneously therewith the disk 45 21 is turned so that the trip arm or extension 27 will travel onto the cam 26, depressing the plate 25, which causes the lifting of the detent 29 for disengaging it from the notch 33 in the bolt 12, and while the arm or 50 extension 27 is traveling upon the cam 26 the forked arm 22 is moved so that its fork 23 will act upon the lug 24 to shift the bolt 12 to retracted position against the tension of the spring 34, and when the said bolt has 55 been fully retracted the door is free to be opened. On swinging the door to opened position the bolt 12 will be held in its unlatched position so that on the closing of the door the same will be latched automatically 60 under the action of the spring 34 acting upon 65

the said bolt 12 without the use of the crank or key 22, thus it being seen that when the door is locked the detent 29 will engage in the notch 33 in the bolt so that it cannot be pushed inwardly from without the car, 70 thereby preventing a surreptitious entry to the same, as an entry can only be made when the crank or key 22 is used for the turning of the shaft 15 to operate the lock mechanism for the door. 75

It is of course to be understood that in lieu of the use of a single latch bolt 12 any number of the same may be employed and their operation effected in a manner as hereinbefore set forth. 80

From the foregoing description, taken in connection with the accompanying drawings, the construction and manner of operation of the device will be clearly understood, and therefore a more extended explanation 85 has been omitted.

What is claimed is:—

1. The combination with a sliding door for a car, of locking mechanism comprising a sliding bolt movable into the path of movement of the door for fastening the same closed, a shaft mounted within the car and exposed at one end through the bottom thereof, a locking detent engageable with the bolt when fastening the door, and means 90 actuated by the shaft for synchronously releasing the detent and throwing the bolt. 95

2. The combination with a sliding door for a car, of locking mechanism comprising a sliding bolt movable into the path of movement of the door for fastening the same closed, a shaft mounted within the car and exposed at one end through the bottom thereof, a locking detent engageable with the bolt when fastening the door, means 100 actuated by the shaft for synchronously releasing the detent and throwing the bolt, and means for automatically resetting the bolt when the door has been closed. 105

3. The combination with a sliding door for a car, of locking mechanism comprising a sliding bolt movable into the path of movement of the door for fastening the same closed, a shaft mounted within the car and exposed at one end through the bottom 110 thereof, a locking detent engageable with the bolt when fastening the door, means actuated by the shaft for synchronously releasing the detent and throwing the bolt, means for automatically resetting the bolt 115 when the door has been closed, and means for gravitating the detent on the resetting of the bolt for locking engagement therewith. 120

4. The combination with a sliding door for a car, of locking mechanism comprising a sliding bolt movable into the path of movement of the door for fastening the same closed, a shaft mounted within the car and exposed at one end through the bottom 125 130

thereof, a locking detent engageable with the bolt when fastening the door, means actuated by the shaft for synchronously releasing the detent and throwing the bolt, 5 means for automatically resetting the bolt when the door has been closed, means for gravitating the detent on the resetting of the bolt for locking engagement therewith, and means for detachably engaging the

shaft from without the car for operating 10 said shaft.

In testimony whereof we affix our signatures in presence of two witnesses.
